RECEPTACLE

Benjamin F. Conner, West Hartford, Conn., assignor to Colt's Patent Fire Arms Manufacturing Co., Hartford, Conn., a corporation of Connecticut

Application June 24, 1932, Serial No. 619,048

Renewed April 9, 1935

1 Claim. (Cl. 215—1)

The invention relates to a receptacle of an ornamental character, and particularly to a receptacle having a plurality of parts which may be molded from artificial resins or other moldable materials and which may be combined to provide an ornamental contour and to provide different combinations of colors.

In the accompanying drawing I have shown the principal embodiment of the invention which I now deem preferable, and two modifications of such embodiment, but it will be understood that the drawing is intended for illustrative purposes only and is not to be construed as defining or limiting the scope of the invention, the claim forming a part of this specification being relied upon for that purpose.

Of the drawing:

Fig. 1 is a combined elevational and sectional view of a receptacle embodying the invention and also of a cover therefor.

Fig. 2 is a vertical transverse sectional view of the upper member of the receptacle.

Fig. 3 is an elevational view of the main member of the receptacle.

Fig. 4 is a vertical transverse sectional view of the lower member of the receptacle.

Fig. 5 is a fragmentary view similar to Fig. 1, but showing a modified embodiment of the invention.

Fig. 6 is another fragmentary view similar to Fig. 1, but showing another modified embodiment of the invention.

Referring to the drawing, 1 is a hollow cylindrical member which constitutes the main member of the receptacle. This member is shown as provided with an integral bottom 2, but as to this I do not necessarily limit myself. The member 1 is provided adjacent its upper edge with a plurality of external ribs or threads 3, 3 and it is provided adjacent its lower edge with a plurality of external ribs or threads 4, 4.

The upper member 5 of the receptacle is annular and its lower portion is of such size as to be adapted to surround and approximately fit the upper portion of the main member 1. The said upper member 5 is provided with a plurality of internal ribs or threads 6, 6 which are adapted to engage the threads 3, 3 on the main member as indicated in Fig. 1. Formed within the upper member 5 is a downward facing annular shoulder 7 which engages the top edge of the main member. It will be understood that when the upper member is assembled with the main member, the shoulder on the upper member is forced by the threads into firm engagement with the

top edge of the main member, with the result that the two members are frictionally held against rotative movement in the unlocking direction. Adjacent its top edge the upper member 5 is provided with an annular rabbet 8 which is adapted to receive an annular flange 9 on the cover 10.

The lower member 11 of the receptacle is annular and its upper portion is of such size as to be adapted to surround and approximately fit the lower portion of the main member 1. The said lower member 11 is provided with a plurality of internal ribs or threads 12, 12 which are adapted to engage the threads 4, 4 on the main member as indicated in Fig. 1. Formed within the lower member is an upward facing annular shoulder 13 which engages the bottom edge of the main member. It will be understood that when the lower member is assembled with the main member, the shoulder on the lower member is forced by the threads into firm engagement with the bottom edge of the main member, with the result that the two members are frictionally held against rotative movement in the unlocking direction. The before-mentioned annular shoulder 13 may constitute the peripheral portion of an integral bottom wall 14 extending entirely across the lower member 11.

Inasmuch as the lower portion of the upper member 5 and the upper portion of the lower member 11 do not closely fit the corresponding portions of the main member 1, I prefer to provide the said main member 1 with annular ribs 15 and 16 which serve to close the annular openings and thus enhance the appearance of the receptacle.

In Fig. 5 I have shown an alternative embodiment of the invention, wherein the bottom wall 14 of the lower member is omitted, there being provided in lieu thereof an annular ledge providing an upward facing shoulder 13a.

In Fig. 6 I have shown another alternative embodiment of the invention, wherein the bottom wall 2 of the main member 1 is omitted, the bottom wall 14 of the lower member thus constituting the main bottom wall of the receptacle.

The construction which I have shown and described makes it possible for the receptacle to be provided with certain desirable and ornamental exterior designs, such for instance as the design shown. It will be observed that the upper and lower members have diameters greater than that of the main member, each of them being illustrated as comprising a series of annular surfaces of successively greater diameters. It is obvious

that the receptacle as an entirety could not be successfully or conveniently molded if an attempt were to be made to mold it all in one piece.

Furthermore I prefer to provide the receptacle with different colors for different parts thereof. For example, the body member 1 and the cover 10 may be white, and the upper and lower members 5 and 11 may be red. Various other color combinations will be obvious. It will be clear 10 that these varying colors could not be obtained if an attempt were made to mold the entire receptacle as one piece.

By providing three separate pieces, as shown and described, I have made it possible for molding 15 to be easily and economically effected, and I have also made it possible for any desired colors to be utilized and combined in any desired way. It will be understood that the main member, the upper member and the lower member may be molded 20 separately and in any desired variety of colors. By selecting for assembly parts of different colors any desired color combination can be obtained. It will further be understood that the parts can be very quickly assembled, it being only necessary 25 to give each of the upper and lower members a fractional turn with respect to the main member to firmly lock it in place.

What I claim is:

A receptacle comprising in combination, a main hollow cylindrical member closed at the bottom and of substantially uniform exterior diameter throughout, the said member being provided adjacent its lower edge with a plurality of external helical ribs or threads and an external annular rib above the threads and being provided adjacent its upper edge with a plurality of external ribs or threads and an external annular rib below the threads, an annular lower member having its upper portion surrounding and approximately fitting the lower portion of the main member, the said lower member approximately engaging the lower annular rib on the main member and being provided with a plurality of internal helical ribs or threads engaging the lower threads on the main member, and an annular upper member open at the top and having its lower portion surrounding and approximately fitting the upper portion of the main member, the said upper member approximately engaging the upper annular rib on the main member and being provided with a plurality of internal helical ribs or threads engaging the upper threads on the main member. 10 15 20 25

BENJAMIN F. CONNER.
